DESCRIPTION

U.S. PATENT DOCUMENTS

FIG. 1 is a perspective view of an envelope shaped as an house, showing my new design;

D137,686 S * 4/1944 Maienthau D19/28
D274,916 S * 7/1984 Hunt D19/28
D298,694 S * 11/1988 Sass D3/18
D318,302 S * 7/1991 Ostrander D21/475
D344,627 S * 3/1994 Hochman D3/211
D350,692 S * 9/1994 Seki D9/636
D431,456 S * 10/2000 Davis D9/636
6,148,550 A * 11/2000 Niedfeld 40/124.06
D486,856 S * 2/2004 Doctor D19/34

FIG. 2 is a front elevational view thereof; the rear elevational view is a mirror image thereof;

FIG. 3 is a right-side elevational view thereof;

FIG. 4 is a left-side elevational view thereof;

FIG. 5 is a top plan view thereof; and,

FIG. 6 is a bottom plan view thereof.

The broken lines and surface indicia are included for the purpose of illustrating environmental structure and form no part of the claimed design.
